UNITED STATES PATENT OFFICE.

WILLIAM H. NAYLOR, OF PHILADELPHIA, PENNSYLVANIA, ASSIGNOR TO THE NAYLOR MANUFACTURING COMPANY, OF CAMDEN, NEW JERSEY.

STRANDING AND BAND-TWISTING MACHINE.

SPECIFICATION forming part of Letters Patent No. 451,569, dated May 5, 1891.

Application filed May 6, 1890. Serial No. 350,772. (No model.)

To all whom it may concern:

Be it known that I, WILLIAM H. NAYLOR, a subject of the Queen of Great Britain and Ireland, residing at Philadelphia, Pennsylvania, have invented certain Improvements in Stranding and Band-Twisting Machines, of which the following is a specification.

My invention relates to certain improvements in the band-twisting machine for which Letters Patent were granted me on the 4th of March, 1890, No. 422,611.

My present invention relates to mechanism for stranding the yarn and to details in the construction of the machine.

15 In the accompanying drawings, Figure 1 is a longitudinal sectional view of my improved band-twisting machine. Fig. 2 is a plan view thereof. Fig. 3 is an enlarged end view thereof, partly sectional. Figs. 4, 5, and 6 are views 20 of details of the invention, and Fig. 7 is a diagram showing the manner in which the yarn is stranded.

The general construction of the machine in regard to the twisting mechanism is of the 25 general plan shown and described in the above-mentioned patent and need not be fully described.

30 A is the bed of the machine, composed of two longitudinal bars and the end-supporting frames or legs.

B is a longitudinal shaft having its bearings in said legs, and is driven from the driving-shaft C, which is provided with fast and loose pulleys c c'.

35 On the shaft is a sleeve C', having bevel gear-wheels d d', adapted to mesh alternately with a bevel gear-wheel b on the shaft B, the bevel gear-wheel d meshing with the wheel b when the strand is on the two hooks described 40 hereinafter, and the bevel gear-wheel d' meshes with the wheel b when the strand has been removed from the two hooks and placed on the single hook, described hereinafter.

On the sleeve C' is a worm d², meshing with 45 a worm-wheel D¹⁷, which is mounted on the shaft D, (shown by dotted lines in Fig. 2,) having its bearings in the frame of the machine similar to that shown in the above-described patent. On this shaft D is a cam D', 50 (see Fig. 3,) having in the present instance pins e e', which act on levers, described here-

inafter, for operating different parts of the machine; but the pins may in some instances project directly from the shaft without departing from my invention. The sleeve is 55 moved on the shaft by a handle E, having a spring-actuated lever E', provided with a pin e² at its lower end adapted to pass in one of the series of orifices in a plate E², so that by moving the sleeve longitudinally through the 60 medium of the handle either one or the other of the bevel-wheels will be thrown into gear with the bevel-wheel b.

On the shaft B is a gear-wheel B', meshing with pinions f f on spindles F F, carrying at 65 their inner ends the hooks h h, on which the strands to be twisted are placed.

On the shaft B is a friction-wheel B², and mounted on a pivoted arm G is a shaft G', carrying a friction-pinion g and a hook g' at 70 its inner end. The arm G is pivoted at g' to the frame, and has an extension or arm G² bent as shown in Fig. 3 and weighted. Engaging with this arm is a catch-lever H, pivoted at h' to the frame of the machine. This 75 catch-lever is weighted at its outer end. The arm G² is released from the control of the catch-lever by the pin e' striking against a projection on the catch-lever and depressing it, so that the arm will be free from the catch 80 and the weight will move the friction-pinion g into engagement with the friction-wheel B². The pinion is thrown out of engagement with the friction-wheel by hand, the operator grasping the shaft or spindle G'. 85

Sliding on the frame of the machine is a carriage I, carrying the spindle J, having a hook j at its inner end. This hook receives the single end of the strand of yarn to be twisted. A pinion j' on this spindle J meshes 90 with a gear-wheel k, loose on the shaft B, but adapted to slide with the carriage I, being connected to it through the medium of a sleeve and link similar to that described in the above-mentioned patent. 95

On the gear-wheel is a disk k', adapted to engage with the disk k², adapted to slide on but turn with the shaft V. A weighted sleeve k³ back of the disk is connected by a cord j² to a weight K, this cord passing around a pulley on the frame and a pulley on the weight, and is secured to the rear of the carriage I 100

in the same manner and for the same purpose as in the above-described patent.

Adapted to bearings on the frame is a longitudinal shaft L, having tappets l, adapted to raise one side of the carriage and lift the pinion j' out of engagement with the gear-wheel. When the twisting has reached a certain point, the shaft L is operated in time by the cam D' on the shaft D striking a pivoted arm L', which is connected by a link L² to an arm l' on the shaft L, Fig. 3.

S is a slide adapted to the bed A, and carries a pin s, which rests between the two strands of the cord as it is twisted, as clearly described in the patent alluded to above. This slide, when it is forced forward by the twisting of the band, comes in contact with a trigger S', pivoted at s', and having a weighted toe s², which rests in front of a projection t on the shifting-bar T. As soon as the long arm of this lever is tripped it releases the shifting-bar from its control, and the weight T' forces the belt-shifter from the fast to the loose pulley. The operator can return the belt to the fast pulley by simply turning the shaft T² by its handle t', this shaft being connected to the belt-shifter by a strap t². When the second twist is finished—that is, the twist put in by the hook-spindle G'—the pin e on the cam D' strikes the arm u of a lever U, this arm u being adjustably secured to said lever. The lever is pivoted at U' to the shifting-bar T. Hence the opposite end of the bar is lifted and strikes the toe s², releasing the bar T from the control of the toe. As soon as the bar is reset the weight s³, attached to the toe, is sufficient to force the toe to drop in position again.

Mounted on the rear of the machine are two brackets M and N. The bracket M carries a shaft M' and a spindle M². The shaft M' has fast and loose pulleys m m', connected by a belt to a pulley c² on the shaft C.

On the shaft M' is a pulley m², and on the spindle is a pulley m³. The pulley m² is a driven pulley, and passing over the two pulleys m² m³ is a belt, which also passes around pulleys n n' on spindles N' N², adjustably secured on the slotted frame N by means of nuts adapted to screw-threads on the spindles, as shown in Fig. 2. The belt first passes around the pulley m², then around the pulley n', then back around the pulley m³, and finally around the pulley n, as shown in Fig. 1. Carried by this belt P is a thread-guide p, having a wing p', which rests upon the threads as they are wound around the spindle. The thread-guide is swiveled on the belt, as clearly shown in Fig. 4.

Q is a thread-guide through eyes on which the threads that make up the strand pass from the bobbins. Suitable tension devices may be applied, when necessary, to give an even tension to the threads as they are fed to the machine.

R is a post projecting upward from the bed and bent, as shown in Fig. 5, and has two bent

pins or hooks r r. The yarn as it comes from the guide Q is first passed through the guide p on the belt, the end being secured to the pins r r, after which the machine is set in motion, and as the belt is moved the yarn is first wound around the shaft M', then around the spindle N², then back and around the spindle M², and then again around the spindle N². As the spindle N' does not extend beyond the pulley, the loop consequently passes around the spindle N². After the yarn has been sufficiently stranded the mechanism is stopped and the yarn broken, the two ends of the strand being twisted in the strand thus formed, which is moved on the spindles and placed upon hooks, the free end of the yarn being twisted around the pins r r ready for the stranding of a new strand.

I prefer to automatically stop the stranding apparatus and secure to the belt a projecting pin v, which strikes in succession the pins v' on the disk V, mounted in a bearing on the frame of the machine. The disk has a projection v², preferably forming a continuation of one of the pins, and extending in the path of this projection v² is an arm v³ on a shaft V', which carries at its opposite end an arm v⁴, so that in the present instance after the fourth complete revolution of the belt P the projection v² will strike the arm v³ and throw the arm v⁴ up in the direction indicated by the arrow in Fig. 3, striking the shifting-bar V², which is held in the position shown in Fig. 3 by a projection w, engaging with the frame of the machine; but as soon as the arm lifts the shifting-bar it frees its catch, and the weight w' throws the belt from the fast to the loose pulley. This mechanism determines the number of lengths of yarn in the strand.

A guide p² on the frame N, which extends around the pulley n, tends to keep the thread-guide in its proper position as it passes around the pulley.

The spindle on which the band is stranded may be increased to three or more without departing from my invention, the construction depending altogether on the band or rope to be formed.

It will be seen that by combining stranding mechanism with the twisting mechanism while the machine is twisting one band it is also stranding another, so that as soon as the twisted band is finished and removed from the machine the strand, as shown in Fig. 7, can be removed from its spindles and placed upon the hooks, the process of twisting the band being similar to that described in the above-mentioned patent.

I claim as my invention—

1. The combination of band-twisting mechanism with stranding mechanism so geared together in a machine that as the band is being twisted the yarn for the following band will at the same time be stranded ready for application to the twisting mechanism, substantially as described.

2. The combination, in a stranding-machine, of the spindles on which the yarn is stranded, a stranding-belt, pulleys over which the belt passes, and a guide on said belt for the yarn, substantially as set forth.

3. The combination, in a stranding-machine, of the belt having a thread-guide and a fixed point to which one end of the thread is secured, with pulleys m^2 m^3 , the pulley m^3 being situated above the pulley m^2 , and pulleys n and n' in a horizontal line, so arranged that the yarn to be stranded will form a single loop at one end and two independent loops at the opposite end, substantially as described.

4. The combination of the stranding-belt, its pulleys and thread-guide, a pin v on the belt, a disk having pins against which the said pin on the belt strikes a projection on the disk, a shaft having an arm in the path of the projection with a belt-shifter bar, and an arm on said shaft adapted to release the shifter-bar, substantially as described.

5. The combination of the belt and a thread-guide on said belt, having a wing p' adapted to rest upon the thread or yarn as it is being

stranded to keep the guide in its proper position, substantially as described.

6. The combination of the driving-shaft, the sleeve having a worm thereon, the shaft D, a worm-wheel thereon meshing with said worm, and a cam on said shaft D acting to lift the carriage and having pins $e e'$, one pin acting to release the arm carrying the friction-wheel and the other pin acting to release the shifting-bar, substantially as described.

7. The combination of the driving-shaft, the cam-shaft geared thereto, a pin or projection carried thereby, a belt-shifting bar, a toe engaging with a projection on said bar, and a trip-lever carried by the bar, adapted to be acted upon by the pin or projection on the cam-shaft and lift the toe, whereby the shifting-bar is released, substantially as set forth.

In testimony whereof I have signed my name to this specification in the presence of two subscribing witnesses.

WILLIAM H. NAYLOR.
